UNITED STATES PATENT OFFICE.

ALFRED WEBER, OF NEW YORK, N. Y.

DESIGN FOR AN INCANDESCENT-LAMP BULB OR SIMILAR ARTICLE.

Application filed July 19, 1928. Serial No. 27,529. Term of patent 7 years.

To all whom it may concern:

Be it known that I, ALFRED WEBER, a citizen of Austria, and a resident of the borough of Queens, in the city and State of New York, have invented a new, original, and ornamental Design for an Incandescent-Lamp Bulb or Similar Article, of which the following is a specification, reference being had to the accompanying drawing, forming part thereof.

In the said drawing, the figure is a perspective view of an incandescent lamp bulb or similar article, showing my new design.

I claim:

The ornamental design for an incandescent-lamp bulb or similar article, substantially as shown.

In witness whereof I have hereunto signed my name this thirteenth day of July, 1928.

ALFRED WEBER.
